UNITED STATES PATENT OFFICE

2,037,543

ELECTRIC CABLE

Charles E. Seaberg, Bridgeport, Conn., assignor
to General Electric Company, a corporation of
New York

Application February 21, 1935, Serial No. 7,466

2 Claims. (Cl. 173—264)

My invention relates to electric cables, and more particularly to a low voltage supply cable for outdoor use.

The object of my invention is to provide an improved cable for low voltage supply which is highly resistant to atmospheric conditions, has increased flexibility and will withstand hard usage.

What I consider to be novel and my invention will be better understood by reference to the following specification and appended claims when considered in connection with the accompanying drawing, in which the single figure is a plan view of my cable with layers of insulation cut away 15 to expose the layer beneath.

Referring to the drawing, 10 indicates an electric conductor which, as shown, is a solid copper wire though it may be stranded. Over the conductor 10, a layer of rubber insulation 11 is provided. Over the rubber a fibrous braid 12 is located. Braid 12 is impregnated with a weather proofing material. A paper tape 13 is wound spirally over the braid 12. A second conductor 14 consisting of a large number of small diameter strands is wound with a long pitch spiral over the paper tape 13. The paper tape 13 beneath the stranded conductor 14 serves to protect the insulation from injury upon the bending of the cable which might result due to the compression 30 of the strands on the under side of the bend which would cut into the insulation and thus reduce the insulation between the two conductors 10 and 14 which might result in a breakdown of the cable. In addition, the paper tape 35 beneath the stranded conductor 14 permits relatively free movement of the conductor 14 with respect to the remainder of the cable. This increases the flexibility of the cable. Over the conductor 14 a paper tape 15 is wound spirally 40 completely covering the conductor 14. Over the paper tape 15 a braid 16 of fibrous material is provided. Braid 16 is impregnated with a weatherproofing and fire resistant material 17 such as pitch or the like which permeates the braid 16

and covers the paper tape 15. The paper tape, 15 prevents the weatherproofing compound 17 from covering the conductor 14 which would interfere with the connecting of the conductor to the circuit and would require that the compound 5 17 be washed away by a solvent or scraped from the strands of the conductor. In addition, the paper 15 increases the flexibility of the cable by preventing the sticky compound and the braid 16 from tightly engaging the conductor 14 and 10 limiting the ability of the conductor to slide or slip within the cable upon the bending of the cable. It may be found desirable in some cases in which less free movement of the conductor 14 is required to impregnate either tape 13 or 15 15 or both of these paper tapes with a sticky substance which will not interfere with the connecting of the cable to a circuit but will somewhat limit the movement of the conductor 14 within the cable.

From the foregoing, it may be seen that an improved cable is provided which is highly resistant to atmospheric conditions which is flexible and easy to install or connect to a supply circuit.

What I claim as new and desire to secure by Letters Patent of the United States, is:—

1. An electric cable comprising a conductor, a rubber covering over the conductor, a fibrous braid over the conductor, a layer of paper over 30 the braid, a conductor wound spirally over said layer of paper, a second paper layer over the conductor, and an overall fibrous covering impregnated with a weatherproofing compound.

2. An electric cable comprising a conductor, 35 a rubber covering over the conductor, a fibrous braid over the rubber, a paper tape wound spirally over the braid, a stranded conductor wound spirally over the paper tape, a second paper tape wound spirally over said last-named conductor, 40 and a fibrous covering over the second paper tape impregnated with a weatherproofing compound.

CHARLES E. SEABERG.
